WALL RACK OR THE LIKE

Robert S. Morris, Dudley, Mass., assignor to American Optical Company, Southbridge, Mass., a voluntary association of Massachusetts

Filed July 6, 1961, Ser. No. 65,824

Term of patent 3½ years

(Cl. D33—3)

Fig. 1

Fig. 2

Fig. 3

Fig. 4

Fig. 5

Fig 6

FIG. 1 is a plan view of a wall rack embodying my new design;

FIG. 2 is a front elevational view of the wall rack;

FIG. 3 is a rear elevational view of the same;

FIG. 4 is an elevational view of one end of the wall rack;

FIG. 5 is an elevational view of the opposite end of the same; and

FIG. 6 is a front perspective view of the wall rack.

The dominant features of my new design are shown by full lines in the drawing.

I claim:

The ornamental design for a wall rack or the like, substantially as shown and described.
